UNITED STATES PATENT OFFICE.

GEORGE W. WISE, OF GLENFIELD, PENNSYLVANIA.

CURTAIN-POLE.

SPECIFICATION forming part of Letters Patent No. 731,259, dated June 16, 1903.

Application filed March 6, 1903. Serial No. 146,487. (No model.)

To all whom it may concern:

Be it known that I, GEORGE W. WISE, a citizen of the United States of America, residing at Glenfield, in the county of Allegheny and State of Pennsylvania, have invented certain new and useful Improvements in Curtain-Poles, of which the following is a specification, reference being had therein to the accompanying drawings.

This invention relates to certain new and useful improvements in curtain-poles; and the object of the invention is to construct a curtain-pole by means of which the curtains may be readily secured in position and draped as may be desired without the aid of the ordinary rings and pins.

Briefly described, the invention comprises, in connection with the pole proper, a locking-bar preferably engaging with the upper face of the pole, and to this end the upper face of the pole will be provided with a flattened surface. This locking-bar is actuated through the medium of a pair of links hinged or pivoted together at one end and at their outer ends hinged or pivoted to actuating-cams, which are pivotally mounted in the curtain-pole near the pivoted links, which pull upwardly at the center for elevating the cams in such a manner as to raise the securing-bar away from the pole in order to permit the insertion of the edges of the curtains into position or to remove the curtain from the pole; but when these pivoted links are forced downwardly into alinement with each other the cams carry the locking or securing bar therewith and bind the same against the curtain.

All the above construction will be herein-after more fully described, and specifically pointed out in the claims, and in describing the invention in detail reference is had to the accompanying drawings, forming a part of this specification, and wherein like numerals of reference indicate like parts throughout the several views, in which—

Figure 1 is a front elevation of my improved curtain-pole, showing the curtains in position therein. Fig. 2 is a top plan view of the curtain-pole with the knobs thereof removed and the locking or securing bar in the closed position. Fig. 3 is a longitudinal sectional view of the pole with the locking or securing

bar in the closed position. Fig. 4 is a detached detail perspective view of the locking or securing bar. Fig. 5 is a sectional view 55 of the pole, showing the pivoted links or cams in the elevated position in full lines and the position of the locking or securing bar when elevated in dotted lines. Fig. 6 is a detached detail perspective view of one of 60 the actuating-cams.

To put my invention into practice, I provide a pole, which may be of the ordinary cylindrical form, and cut the same longitudinally to produce a locking or securing bar 2. 65 This locking or securing bar is provided near each end with openings 3, the outer wall of said openings being inclined, as shown at 4, and the openings being connected by means of the longitudinal groove 5 in the upper face 70 of the locking or securing bar 2. The pole 1 is provided with recesses 6, in which are pivotally mounted the cams 7, the cam-surfaces 8 of which are adapted to engage with the inclined walls 4 of the recesses and the tenons 9, 75 on the upper face of which cams are adapted to engage through the openings 3 in said locking or securing bar. Pivoted or hinged to the upper face of the tenons 9 of these cams, as at 10, are the outer ends of a pair of links or 80 rods 11, pivotally connected together at their inner ends and carrying a suitable eye 12 or other form of catch by means of which the rods may be elevated. These rods when in the closed position are adapted to have their 85 pivotal point lie slightly below the center of the longitudinal line, and the rods are embedded in the groove 5 of the locking or securing bar. The curtain 14 is placed on the flat upper face of the pole and held firmly by 90 the securing rod or bar 2, being forced into engagement therewith. The knobs 14' may be screwed into the ends of the pole or affixed thereto in any other desired manner. The elevating of the rods or links 11 in the manner shown in Fig. 5 of the drawings will cause the cam 7 to elevate the locking or securing bar 2 in the manner shown in dotted line in said view, and when pressure is exerted on the pivoted ends of the rods or links 11 the 100 same are forced down into the groove 5, causing the cams to engage the inclined cam-faces 4 of the securing or locking bar and force the latter into engagement with the curtain. Suf-

ficient space is provided between the outer face of the cams and the edge of the pole in order that the curtain may be gripped by the securing-bar opposite the cams, as well as throughout the remainder of the length of the pole. Curtains of delicate fabrics may be advantageously held without danger of injuring the same. The curtains may be easily and quickly either placed in position or removed therefrom, and the pole may be supported in any suitable or desirable bracket.

It will be observed that various changes may be made in the details of construction without departing from the general spirit of my invention.

Having fully described my invention, what I claim as new, and desire to secure by Letters Patent, is—

1. A curtain-pole provided in its upper face near each end with recesses and having a flattened upper face, cams pivotally mounted in said recesses, a locking or securing bar having openings to receive said cams, links or rods pivoted to said cams and pivoted together at their inner ends, and a catch carried by the inner ends of said rods or links

for operating the same, substantially as described.

2. In a curtain-pole, a pole proper having recesses, cams pivotally mounted in said recesses, a locking or securing bar having openings to receive the upper ends of said cams and provided with inclined or cam faces to be engaged by said cams, and a pair of locking rods or links having their outer ends pivoted to the cams and their opposite ends pivoted together, substantially as described.

3. A curtain-pole comprising a stationary member and a movable member, cams pivotally mounted in the stationary member and engaging the movable member, and locking rods or links pivotally mounted to said cams and being pivoted together for actuating the same to move the movable member and also to lock the same against the stationary member, substantially as described.

In testimony whereof I affix my signature in the presence of two witnesses.

GEORGE W. WISE.
